FUEL DISTRIBUTOR

Howard P. Anderson, Erie, Pa., assignor to The
Standard Stoker Company, Inc., a corporation
of Delaware

Application September 21, 1933, Serial No. 690,364

5 Claims. (Cl. 110—101)

My invention relates to fuel distributors for mechanical stokers and appertains particularly to fuel distributors which are made in two or more separable sections.

One object of this invention contemplates the provision of an improved two section distributor wherein the one section is constructed in the form of a pressure fluid jet head and the other section in the form of a distributing table and in which construction a novel relation exists between the pressure fluid blasts and the distributing table.

A further object of the invention is the provision of a novel distributing table constructed as a perforated hollow shell having an open side and with its walls arranged to prevent distortion of the fuel distributing surface and to protect it from the fire.

A still further object of this invention is the provision of means, in a fuel distributor of the two section type, which prevents displacement and particularly accidental displacement of the removable section.

The advantages and use of the invention will be particularly described in connection with a fuel distributor for locomotive stokers as illustrated in the accompanying drawings, and it will be clear that its use is not necessarily restricted in its association as illustrated by the drawings in which

Figure 1 is a central vertical longitudinal section through a portion of the back wall of a locomotive firebox showing in a similar section a stoker in which my invention is embodied;

Figure 2 is a plan section taken on the line 2—2 of Figure 1;

Figure 3 is an isometric view of the pressure fluid jet head and the distributing table in assembled relation with parts broken or cut away to illustrate particularly the form of these two members and the novel method of holding these two sections in assembled relation;

Figure 4 is an isometric view of one of the safety pins which coacts with the jet head and the distributing table to prevent accidental displacement of the distributing table;

Figure 5 is a sectional view taken on the line 5—5 of Figure 2;

Figure 6 is an isometric view of the shell-like fuel distributing table;

Figure 7 is a plan view on a reduced scale of the jet head and the distributing table, showing the pressure fluid chambers and passages in the jet head more or less diagrammatically; and

Figure 8 is a fragmentary sectional view of

the jet head and the distributing table illustrating another use of the pin shown in Figure 4.

My improved fuel distributor may be used with most forms of furnaces, but as shown in Figures 1 and 2 it is especially adapted for use with a locomotive firebox 10, having the backhead 11 in which there is a firing opening 12, preferably, of the conventional form used on stoker fired locomotives and having its inner marginal edge bounded by the well known "O'Connor flange" 13, which constitutes a part of the backhead 11. The "O'Connor flange" 13 in effect forms a bulge in the backhead and among its advantages is that of deflecting the flames of the fire away from the opening 12 toward the firebox arch (not shown). The novel fuel distributor to which this invention is predicated is indicated as a whole at D and is disposed in or adjacent the lower portion of the firing opening 12 in a position to receive fuel from the stoker conduit C.

In the specific embodiment herein shown as illustrating but one of many different forms of my invention, the distributor D consists of the front section or distributing table 14 and the rear section or jet head 15. The two sections are preferably interlocked within the confines of the backhead 11 as will presently appear. In effect, the jet head 15 forms a continuation of the floor of the conduit C and may be rigidly, but detachably, secured therein by any suitable fastening means. The fastening means herein illustrated will not be described as it forms no part of the present invention. Fuel is advanced through the conduit C to the distributor D by the screw conveyor 16 leading from a source of fuel supply. Any desired mechanism may be employed for driving the screw conveyor 16 and likewise any suitable means may be used for mounting the conduit C on the firebox backhead or in any suitable relation with the firing opening 12 so as to feed fuel therethrough.

It is customary to construct sectional distributors of the character referred to with the front section readily removable from the rear section. Usually this is accomplished by the provision of interlocking elements on the sections holding them in normal position but permitting the front section to be readily removed from the rear section. An important part of the invention here is the inclusion with such an interlocking sectional distributor of means for preventing accidental displacement of the front section, at such times, for instance, when the fireman is using a fire hook or rake.

The jet head 15 is provided with a front face 17 and extending forwardly from the lower edge of this front face is a ledge 60 which serves to support the overhanging weight of the distributing table 14 and restrains downward movement of the table about its interlocking hinge connection with the jet head 15 as will hereinafter be more fully described. The upper surface of the distributing table 14 is in the form of a plate 18, and depending from the rearward underside of the plate 18 are the rearwardly extending lugs such as 19, one at each side portion of the distributing table. The lugs 19 are each provided with an upstanding curved rib such as 20, each of which ribs cooperates with a complementary curved wall 21 of the jet head 15 to hingedly connect the jet head 15 and the table 14.

This construction permits the jet head 15 and the distributor table 14 to be effectively interlocked and usually a construction of this nature is sufficient to maintain the parts of the distributor D in proper relation at all times. However, under certain conditions, it has been found necessary to take precautionary measures against accidental displacement of the distributor parts by the fireman when hooking or raking the fire. To prevent such accidental displacement of parts, a pin 22 is passed loosely through the vertically aligned holes 23, 24 in each of the lugs 19 and the horizontal walls 25, respectively. Each of said horizontal walls 25 is a part of the jet head 15 but forms in effect a rearward continuation of the plate 18. Each pin 22 includes an enlarged head 26 which fits into a counterbored recess 27 formed in each of the horizontal walls 25 and concentric with the vertically aligned holes 23, 24. The enlarged heads of the pins 22 do not protrude above the upper surface of the horizontal walls 25 and in order that these pins may be easily removed, each of them is provided with a bail 28 which may be raised to the position as indicated in Figure 4. Thus, whenever it is necessary to disconnect the front section of the distributor from the rear section thereof, the pins 22 may be conveniently removed, permitting the front section to be hinged from its engaged position with the rear section.

In Figure 8, a modified form of this feature is shown wherein the pin 22 constitutes an element 50 of the interlocking means between the distributing table 15 and the jet head 14. In this construction, the lugs 19 merely contact the underside of the horizontal walls 25 and upstanding curved ribs such as shown at 20 in Figure 3 are not used 55 for engaging a complementary curved portion of the jet head. However, as in the preferred form of the invention, the pins 22 prevent accidental displacement of the distributor parts and are easily removed for the purpose of disconnecting 60 the table 14 from the jet head 15.

In order to prolong the life of the table 14 and other cooperating parts of the distributor D, the table 14 is made in the form of a perforated hollow shell having an open rearward side and including a bottom wall 30 which inclines from the open rearward side toward the opposite side of the plate 18 and then curves upwardly into the top wall or plate 18 to form a front wall 31. At its opposite ends, the bottom wall 30 curves into 70 the plate 18 to form curving end walls 32, 33. The angle of inclination of the bottom wall 30 closely approaches the direction of the flame travel as it is deflected toward the arch by the bulge of the "O'Connor flange". I have found 75 this to be of considerable advantage in that the

flame does not impinge directly upon the bottom wall 30 and hence its life is prolonged.

The only possible point of flame impingement is at the juncture of the curved front wall 31, the end walls 32, 33 and the forward edge of the plate 18. The section of metal at these points I have made considerably heavier in order that the intense heat may be adequately absorbed and radiated rearwardly to cooler parts of the distributor table. A plurality of ribs such as 34 connect the top wall or plate 18 and the bottom wall 30, serving to strengthen the shell structure of the distributor table 14 and also acting as heat absorbing and conducting or radiating elements. The rearward edge of the hollow shell formed by the bottom wall 30 and the end walls 32, 33 fits the walls of the lower portion of the firing opening closely and in this manner, air entering through the open rearward side of the table is entrained through openings such as 35 which perforate the bottom, end and front walls of the table, cooling the same.

The relation between the jet head 15 and the distributing table 14 is a novel one and has proven in actual service to be very efficient in spreading the coal evenly to all parts of the fire and is of the following construction. Rearward of the front face 17 of the jet head 15 are the upper pressure fluid chambers 36, 37 and the lower pressure fluid chamber 38. Pressure fluid is conducted to the chambers 36, 37 by the leads 36a, 37a respectively, while the chamber 38 receives fluid through the lead 38a. Fluid is introduced into the chambers 36, 37 under a higher pressure than into the chamber 38 and in order that the pressure of the fluid in each chamber may be controlled independently, valves 36b, 37b and 38b are placed in the leads 36a, 37a and 38a respectively. The front face 17 is provided with jet openings 39 which are drilled so as to emit pressure fluid from the chambers 36, 37 and 38; the jet openings 39 preferably are drilled so that they form horizontally and vertically aligned rows of holes. These jet openings sweep blasts of pressure fluid across the plate 18 of the distributing table 14 and are directed so that the vertically aligned holes discharge between the diverging or radiating group of ribs 40, 41, 42, 43 and 44 which are formed on the plate 18.

It will be observed from Figures 1 and 2 that the front face of the jet head is disposed rearward of the bulged portion of the "O'Connor flange" and hence, some means must be provided for diverting some of the fuel to the rear corners of the firebox. To accomplish this, the jet head 15 is provided with the walls 45, 46 each of which extends obliquely from an outer end of the front face 17, and forms the forward limit of the side chambers 47, 48 respectively. Pressure fluid is conducted to these side chambers 47, 48 by the leads 47a, 48a which are also provided with valves 47b, 48b respectively for the purpose of independently controlling the pressure of the fluid in each chamber. Drilled through each wall 45, 46 are the jet openings 50, 51 which are directed so that their axes converge at a common point on the side ribs 40, 44. These side ribs 40, 44 curve outwardly toward the sides of the firebox and their outer extremities terminate forward of the backhead and in a vertical plane which extends transversely of the firebox. It will of course be understood that if the front face 17 of the jet head were disposed forward of the backhead 11, the curved side ribs 40, 44 would not be necessary to deflect fuel to the rear corners

of the firebox. However, I prefer that the front face terminate in the position substantially as illustrated as it has been found by actual use to be of considerable importance in prolonging the life of the distributor D generally and the table 14 in particular.

Having fully described my invention, I now make claim to the following as new and novel in the stoker art.

10 I claim:

1. A fuel distributing table constructed as a hollow shell and in its operative position being open at its rearward side and including a substantially flat top wall, an inclined bottom wall extending upwardly from the open side of the table toward the opposite side and curving upwardly into the top wall to form a front wall and said bottom wall at its opposite ends curving upwardly into the top wall to form end walls, the upper portion of the inclined bottom where it curves to form the front and end walls being of greater thickness than at its lower edge.

2. A fuel distributing table constructed as a hollow shell and in its operative position being open at its rearward side and including a substantially flat top wall, an inclined bottom wall extending upwardly from the open side of the table toward the opposite side and curving upwardly into the top wall to form a front wall and said bottom wall at its opposite ends curving upwardly into the top wall to form end walls, the upper portion of the inclined bottom where it curves to form the front and end walls being of greater thickness than at its lower edge and at least one rib extending between the top wall and the inclined bottom wall.

3. A fuel distributing table constructed as a hollow shell and in its operative position being open at its rearward side and including a substantially flat top wall, an inclined bottom wall extending upwardly from the open side of the table toward the opposite side and curving up-

wardly into the top wall to form a front wall and said bottom wall at its opposite ends curving upwardly into the top wall to form end walls, the upper portion of the inclined bottom where it curves to form the front and end walls being of greater thickness than at its lower edge and at least one of said walls below the upper surface of the top wall being provided with a plurality of perforations.

4. A fuel distributing table constructed as a hollow shell and in its operative position being open at its rearward side and including a substantially flat top wall, an inclined bottom wall extending upwardly from the open side of the table toward the opposite side and curving upwardly into the top wall to form a front wall and said bottom wall at its opposite ends curving upwardly into the top wall to form end walls, the upper portion of the inclined bottom where it curves to form the front and end walls being of greater thickness than at its lower edge, at least one rib extending between the top wall and the inclined bottom wall and at least one of said walls below the upper surface of the top wall being provided with a plurality of perforations.

5. A fuel distributor for stokers comprising a rear section and a front section, each of said sections having an element of an interlocking hinging means for detachably securing the front section to the rear section, said interlocking means comprising a ledge formed with said rear section underlying the rearward side of said front section forming a support therefor, and a pair of lugs formed with said front section underlying the forward side of said rear section, one at each side of said ledge, for restraining downward movement of said front section with respect to said rear section, and a pair of pins each extending vertically loosely through the rear section and engaging a corresponding lug of said front section.

HOWARD P. ANDERSON.
